Fig. 3.

A technical drawing of a mechanical part, likely a bracket or frame. The drawing is labeled 'Fig. 4' at the top left. The part features a central vertical slot with a width of 48. On either side of this slot are two vertical columns. The left column has a height of 52. The right column has a height of 40 and contains a circular hole with a diameter of 47. The overall width of the part is 58.

UNITED STATES PATENT OFFICE.

JACOB LAWERENCE SPARLING, OF BAY CITY, MICHIGAN, ASSIGNOR OF ONE-HALF TO
ADAM SCHEPPER, OF BAY CITY, MICHIGAN.

SHAFT-HANGER.

1,304,401.

Specification of Letters Patent. Patented May 20, 1919.

Application filed March 15, 1918. Serial No. 222,669.

To all whom it may concern:

Be it known that I, JACOB L. SPARLING, a citizen of the United States, residing at Bay City, in the county of Bay and State of Michigan, have invented new and useful Improvements in Shaft-Hangers, of which the following is a specification.

This invention relates to a shaft hanger and one object is to provide a hanger by 10 the use of which a shaft may be properly mounted with reference to a supporting structure, regardless of the exact position of the elements of that structure, the hanger providing all necessary adjustments.

15 A further object is to provide a hanger comprising a main frame including guides and a plurality of yoke members slidably mounted with reference thereto and adapted to be secured in any adjusted position and 20 to mount a box or bearing proper.

25 A further object is to provide in connection with mounting means of the character indicated, a bearing box comprising a plurality of separable box members and an inner shell comprising a plurality of separable members, with means for adjusting the position of the members of the shell and means for adjusting the bearing proper within a yoke member or a plurality of 30 yoke members.

35 A still further object is to provide a bearing box including a plurality of members and a shell mounted therein and spaced therefrom, said shell surrounding the shaft, and providing for the distribution of lubricating material throughout the space within the box and through channels or apertures provided in the members of the inner shell, whereby said lubricating material is constantly fed to the surface to be lubricated.

40 A still further object is to provide in connection with a box specified, means for securing the separate members of the box and providing a grease tight connection.

45 In the accompanying drawings:

Figure 1 is a view in side elevation.

Fig. 2 is a view in vertical section.

Fig. 3 is a section on the line 3-3 of

Fig. 1.

50 Fig. 4 is a section on the line 4-4 of

Fig. 1.

Fig. 5 is a plan view of a box element.

Fig. 6 is a plan view of a section of an inner shell to be located within the box.

55 The frame of the hanger is designated 10

and includes parallelly arranged members 11 and 12 connected by a transverse member 13, members 11 and 12 being connected at their opposite ends by means of a transverse member or yoke 14 detachably secured 60 and held in position by bolts 15 and nuts 16. Members 11 and 12 are provided with inwardly extending guides 17, these guides being provided with apertures 18 permitting the 65 slidable member or members described below to be placed in any desired position lengthwise of the members 11 and 12 to be secured in that position by means of bolts 19 and 20 passing through the apertures 18. 70

A plurality of slidable yokes are mounted between the guides 17, these yokes being designated 22 and 23 and being provided with apertures at the points shown for the accommodation of adjusting bolts 24 carrying jamb nuts 25. 75

Each yoke 22 or 23 is provided with a plurality of laterally extending ears 26 spaced apart and coöperating with the guides 17. The surfaces of members 26 are 80 flush with the meeting edges of the yoke members, these surfaces being channeled at 28 and providing transversely extending apertures through which bolts pass for securing the yokes in adjusted position with 85 reference to the guides. Adjacent to the ears 25 and 26 are laterally extending members 31 and 32 spaced apart and provided with apertures or bores 33 through which bolts 34 pass, these bolts securing the yoke 90 members in position with their meeting edges 35 in contact.

The box in which the shaft is mounted is located as shown with reference to the yoke members and is held in adjusted position by means of devices 24 above specified. 95 The box comprises a plurality of members cylindrical in form and including outstanding portions which encircle the shaft, these portions last named being designated 40 and 41 and the box members proper being designated 42 and 43. Each box member carries a boss 44 centrally located and having a concave surface for engagement with the tapered ends of the adjusting devices 100 above specified. One of the box members includes a plug connection 45 permitting the box to be filled with lubricating material. A plurality of bosses 46 located near the 105 ends of the box provide for set screws for 110

holding the inner shell 47 in position. The inner shell includes a plurality of semi-cylindrical members directly engaging the shaft containing the Babbitt metal, these members being provided with apertures through which lubricating material may pass from the space or chamber 48 between the inner shell and the box proper. The entire space within the box, including that 10 actually occupied by the inner shell is to be filled with lubricant and this material will be forced inwardly toward the shaft, to lubricate the bearing surface at all times. A spacing member 40 is provided on each side 15 of each section of the inner shell and serves to space the latter from the box proper. One section of the inner shell is provided with a boss 50 having a concave surface engaging a convex surface or boss 51 projecting into the shell, and adjustment between the sections on the inner shell is effected by turning the set screws 52 here- 20 to mentioned. A gasket 53 prevents grease from passing out of the side of the 25 box.

The semi-cylindrical members 40 and 41 of the oppositely located box members co-operate to form a sleeve encircling the shaft, and this sleeve in turn encircled by an outer 30 detachable sleeve 55 comprising a plurality of semicylindrical members 56 and 57 having ears 58 formed thereon and said ears being connected by means of bolts or 35 screws 59.

35 This sleeve last named is provided with a reduced portion 60 at the outer end for the accommodation of a felt washer or the like 61 engaging the end portion of the members 40 and 41 constituting the sleeve first named.

40 In the construction described provision is made for unusually efficient lubrication, and for a large variety of adjustments, making it possible to employ the hanger and box in any desired position and to take up wear 45 at any time.

What is claimed is:

1. In a device of the class described, a frame including a plurality of parallel guides, a plurality of yoke members operable 50 between said guides, means for securing the yoke members in various adjusted positions with reference to the guides, a box constituting a bearing, and means for adjustably mounting the box within the yoke members.

55 2. In a device of the class described, a frame comprising a plurality of parallel guides, a plurality of yoke members re- 60 versely arranged with reference to each other and connected with the guides, guid- ing means carried by each of said yoke mem- bers, the guiding means on the oppositely located members being in alinement and co-

operating with the guides first named, means for connecting the yoke members, and a box 65 adjustably mounted between the yoke members and supporting a shaft.

3. In a device of the class described, a plurality of parallelly arranged guides, a plurality of yoke members operating between the guides, means for securing the 70 yoke members in various adjusted positions with reference to the guides, said yoke members being reversely arranged and including laterally extending devices engaging the guides, means passing through the laterally 75 extending devices for retaining the yoke members in position with reference to each other, a box located between the yoke members, and adjusting means connected with the yoke members and retaining the box in 80 an adjusted position with reference to the yokes.

4. In a device of the class described, a plurality of yoke members reversely arranged, means for mounting the latter in an 85 adjusted position and for varying said position, a box comprising a plurality of semi-cylindrical members mounted between the yokes, each of said members being adjustable with reference to one of the adjustable 90 yokes, a shell mounted within said box, and having walls spaced from the inner walls of the box, and means for adjusting the position of the inner shell with reference to the box.

95 5. In a device of the class described, a plurality of yoke members reversely arranged, a box mounted therebetween, means for adjusting the box with reference to the yoke members, a shell mounted within the 100 box and spaced from the walls thereof and provided with apertures for the passage of lubricating material, and means for closing the ends of the box and forming a grease tight connection.

105 6. In a device of the class described, a plurality of yoke members, reversely arranged, means for adjustably mounting a box between the yoke members, a bearing comprising a box formed with the semi-cylindrical sections, said sections having longitudinally extending semi-cylindrical members, a shell mounted within the box and spaced from the walls thereof, a sleeve surrounding the semi-cylindrical extensions 110 on the box, the sleeve being formed in sections detachably connected, said sleeve having a reduced end portion, and a gasket between the reduced end portion and the longitudinally extending members carried by the 115 box sections.

In testimony whereof I affix my signature.

JACOB LAWERENCE SPARLING.
